UNITED STATES PATENT OFFICE.

MARTIANUS ROSS, OF KANSAS CITY, MISSOURI.

TOY GUN.

1,159,098.

Specification of Letters Patent.

Patented Nov. 2, 1915.

Application filed May 20, 1915. Serial No. 29,407.

To all whom it may concern:

Be it known that I, MARTIANUS Ross, a citizen of the United States of America, residing at Kansas City, in the county of Jackson and State of Missouri, have invented a certain new and Improved Toy Gun, of which the following is a specification, reference being had to the accompanying drawing, forming a part of this specification.

The invention has for its object a harmless toy for minors, by means of which the semblance of a fire arm is afforded, with the production of frequent reports, analogous to that of an explosive fulminate exploded by percussion, without its danger.

The invention is further designed for use in the practice of the manual of arms, whereby an inexpensive facsimile of a gun or pistol may be employed for military schools, and it consists in the novel construction and combination of parts, such as will be first fully described and then specifically pointed out in the claims.

In the drawings: Figure 1. is a side view of the toy gun, embodying the invention. Fig. 2. is a top plan view of the same. Fig. 3. is a view from the under side of the gun, as seen in Fig. 1, looking upwardly. Fig. 4. is a vertical, sectional view of the central portion of the body of the gun stock, showing the sound-producing device and repeating trigger. Fig. 5. is an isometric view of the rotatable trigger arms and hub. Fig. 6. is a side view of a facsimile of a pistol, showing the invention applied thereto. Fig. 7. is a side view of the invention, as seen in Fig. 4, showing a modification.

Similar numerals of reference indicate corresponding parts in all the figures of the drawings.

Referring to the drawings, the toy gun as constructed embodies the butt end 7 of the stock 8, and the barrel 9, externally shaped, to correspond to the same parts assembled in an ordinary firearm or rifle, these parts being formed from a single piece of board or plank, of the requisite width and length.

The reduced end of the material which constitutes the barrel 9 extends from a part X, to a bend at point y, about one-third the distance in the direction of the other end or butt end 9, the portion designated as the stock 8 forming an equal division between the barrel 9 and the neck portion 10, of the

butt end 7 of the gun, the under or lower surface of which stock 8 is made broad and flat, as seen at 12. In the lower surface and forward portion of the neck 10, and at the line of the bend y, y, and also in the gun stock 8 is a depression 13, of considerable depth, the sides of which depression are in the arc of a circle.

15 indicates the percussion spring strip or plate, by means of which the adequate report is obtained. The strip may be made from metal or wood, the latter being preferable, the forward end being thin, and from said end rearwardly the strip increases to a slight extent in thickness. The said forward end of the strip is secured fixedly in position to the flat lower surface and forward portion of the stock member 8, at a point through which the line x passes, by means of the screws 16. The rear end of spring strip 15 extends to a point a short distance inwardly from the forward line of the curved depression 13, in the neck 10, and is rounded or curved at 15°, the width of the spring strip or plate 15 being less than that of the surface 10, with which it comes into contact.

17 indicates the series of rotative triggers for actuating the spring strip or depression plate 15. These triggers comprise arms connected at their inner ends eccentrically with the outer surface of a hub 18. The outer ends of the arms or triggers 17 are curved at 19, in a slight degree. The hub 18 is made to extend the width of the depression 13, in the neck 10 of the butt end of the gun, the hub 18 being mounted on a pivot 20, extending transversely through the lower forward portion of the neck 10, upon an axial line with the inner curved surface of the depression 13, the outer ends of the arms or triggers being rotatable therein, the curved surface 19 of one of which arms or triggers bears normally upon the upper surface of the inner end 15°, of the spring percussion plate 15, and another arm normally extending outwardly in position for engagement of the finger of the operator.

Upon the application of pressure to the outwardly extended triggers 17, the rear end of the percussion plate is forced outwardly into the dotted position seen in dotted lines in Fig. 4, and following a continuous pull on said trigger, the trigger engaging with the inner end 15°, of the percussion plate, slips off the said end, and the said plate is

- retracted forcibly inwardly, striking the surface 12 of the gun stock, with great force, and making a report which can be heard a long distance. The application of the finger to the trigger, which operates the percussion plate in succession, causes a repetition of the noise or report, and this can be made as disturbing as the exercise of the fingers is permitted.
- 10 The snap of the percussion plate may be increased by shortening the strip 15, and thus increases resistance of the spring plate in its outward movement, this being dependent upon the elasticity of the strip 15, the 15 increase in thickness of the strip serving to increase the sound or report. Should the inner end of the spring or percussion plate become worn away from frequent use, the screws 16 may be removed and the plate moved backward a slight distance, to compensate for the lost portion, and the screws secured at a new point in rear of the first point of attachment.
- 19 In Fig. 6, I have shown the application 25 of the invention to a toy pistol, which is in precise manner as seen in Fig. 1, the spring percussion plate 22 being obviously made shorter in length than the percussion plate 15.
- 30 The barrel 9 of the gun, is provided with the usual sights 23 and 24, as in any fire arm, hence a squad of men or boys may be thoroughly drilled in the manual of arms, and the arms provided at small cost in the 35 use of the present invention. In order to make the gun of very low cost, no bore is made in the barrel 9, or, if made, only to a slight distance inwardly from the outer end.
- 40 To make a double report from one pull of the trigger, a second spring plate 25 is placed beneath the lower surface of and in contact with the percussion plate 15, as seen in Fig. 7, and secured to the gun stock by the 45 same screws 16. The inner free end of the outer percussion plate 25 extends a slight distance rearwardly from the line of the rear end of the inner percussion plate or strip 15, so that the same trigger operates the ends of the combined percussion strips in 50 succession, obtaining a double report thereby.
- The invention provides means for producing the semblance of the report of a pistol, and without expense and the danger 55 attendant upon the use of such weapon, avoiding the employment of fulminate caps, although such may be used if desired, and to afford a gun which is an everlasting repeater, does not require reloading, and no 60 expense for ammunition.

I am aware that the inventive idea has

been conceded in the rappings of vibrating slats upon a diaphragm, and in a spring operated by trigger arms to eject a marble, and a spring hammer to explode a cap 65 upon rotatable trigger arms, but no one has heretofore made a practical embodiment of a detonator as part of a gun stock, in which the parts may operate and become serviceable in a fire arm, as a hand 70 piece for increasing the muzzle elevation of the gun barrel during the inward movement of the hand, as a detonator in a toy gun, and as a guard for the finger in the manual of arms, as seen at 15^x. I am aware that 75 rotatable triggers are old. In my invention, however, the distinctive part known as the gunstock supports the gun barrel, and no one has heretofore anticipated as a detonating member a separable member of the 80 gunstock, or as an attachment to gunstock, for either one of the purposes described, or any other purpose.

Such modifications may be employed as are within the scope of the appended claims. 85

Having fully described my invention, what I now claim as new and desire to secure by Letters Patent is:

1. In a gun comprising a barrel and a gunstock, a separable spring part or strip 90 attached to the lower side of the gunstock, and means for forcing out and suddenly releasing said spring strip.
2. In a gun comprising a barrel and a gunstock having a longitudinal flattened 95 outer surface, a spring plate attachment attached at its forward end to the said outer flattened surface and forward portion of the gunstock and normally in contact therewith, and means for forcing out and 100 suddenly releasing said spring plate.
3. In a toy gun, a combined gunstock and barrel, and a trigger, and an attachment to the lower surface of the gunstock and secured at its forward end to the forward portion of the said gunstock, and having its rear end increased in thickness to 105 the forward end and adapted to form a finger guard adjacent the trigger.
4. In a toy gun, a gunstock and a barrel, 110 said gunstock having a flattened lower surface, and a flat member or bar having its forward end portion attached fixedly to the forward portion of the gunstock, and rotary bar contacting means for forcing out 115 and suddenly releasing the rear end portion of said flat member or bar.

MARTIANUS ROSS.
